UNITED STATES PATENT OFFICE.

LORENS SWENSON, OF NORTH CAPE, ASSIGNOR TO HIMSELF AND JOHN B. SMITH, OF MILWAUKEE, WISCONSIN.

IMPROVEMENT IN CRANK-EXPANDERS.

Specification forming part of Letters Patent No. 129,996, dated July 30, 1872.

SPECIFICATION.

I, LORENS SWENSON, of North Cape, in the county of Racine and in the State of Wisconsin, have invented certain Improvements in Crank-Expanders, of which the following is a specification:

Nature and Object of the Invention.

My invention consists in a cam placed on a crank inclosed within a frame, so that as the crank in its revolution, when it approaches its position at or nearly at right angles with the pitman, will be thrown out, thereby lengthening the stroke or leverage of the crank, and when it approaches the dead-points of the stroke the cam will shorten the hold of the pitman so as to have the crank pass by those points without increasing the length of the cylinder.

Description of the Drawing forming part of the Specification.

Figure 1 is a perspective view of my invention, and Fig. 2 a sectional view.

General Description.

A is the frame; B, the cylinder; C, the cross-heads; D, the pitman; E, slide in which the cross-head works; F, frame on the end of the pitman, in which the cam works; G, the cam, fastened to the crank; H, a roller in the frame, against which the cam works; I, a pin or roller on the outside end of the frame, against which the cam works; K, pin or bolt through a slot in the frame and through the cam and crank; L, crank; M, crank-shaft; N,

balance-wheel; O, bearings or boxes, in which the shaft M runs.

The cam G is made one size larger than the other, so that the larger side may slip in on one side of the roller H, and the small side presses against the roller, while this wide side strikes against the pin I. This is to regulate the working on the two sides of the stroke piston.

The operation of this invention is: as the crank passes around the cam in its movement it increases the length of the pitman, and on the outstroke, when a half stroke of the piston is performed, a quarter-revolution of the crank is made, and thus a regular motion is performed, and the push of the piston is, out from the center of the crank-shaft, faster than an average of the stroke, and the outer portion of the stroke is performed in the same manner, and thus the stroke is equalized, the cam bringing the piston in as it passes the center, and carrying it out as it approaches the greatest amount of leverage.

Claim.

I claim as my invention—

1. The cam G, constructed as described, for the purpose set forth.
2. The cam G, in combination with the crank L, bearings H and I, pitman D, and frame F, substantially as described, and for the purpose set forth.

LORENS SWENSON.
